PRESSING IRON

Max M. Newman, New York, N. Y.

Application September 23, 1937, Serial No. 165,252

6 Claims. (Cl. 38—73)

My invention relates to a new and improved pressing iron.

One of the objects of my invention is to provide a combination pressing iron and pressing cloth which shall be especially useful for ironing silk fabrics, including neck-ties and the like.

Another object of the invention is to provide a pressing iron with a pressing cloth which is mounted so that the iron can be moved to-and-fro relative to the cloth.

Another object of the invention is to provide automatic means for moistening the pressing cloth.

Other objects of my invention will be set forth in the following description and drawings which illustrate preferred embodiments thereof, it being understood that the above statement of the objects of my invention is intended generally to explain the same without limiting it in any manner.

Fig. 1 is a side elevation of the improved device.

Fig. 2 is a top plan view, part of the representation of the pressing cloth having been omitted, in order to show certain parts more clearly.

Fig. 3 is an end elevation, taken at the left-hand side of Fig. 1, part of the representation of the pressing cloth having been broken away, in order to show other parts more clearly.

Fig. 4 is a sectional view on the line 4—4 of Fig. 2.

Fig. 5 is longitudinal sectional view of the roll on which the pressing cloth is wound. For convenience, this may be designated as the magazine roll.

Fig. 6 is an elevation of the magazine roll, showing how the pressing cloth is connected thereto.

Fig. 7 is a sectional view on the line 7—7 of Fig. 6.

Fig. 8 is a diagrammatic view, similar to Fig. 1, and showing a modification.

In ironing many types of fabric, the practice has been to use a moistened pressing cloth which was wholly separate from the iron. While the industry has developed pressing irons having perforated pressing faces, through which steam was passed to moisten the fabric, such irons have not been suitable for pressing silk and numerous other fabrics.

In pressing such fabrics, and even heavier fabrics, the practice for many years has been to use a pressing cloth which was moistened intermittently.

According to the invention, I provide an at-

achment to the iron, whereby a pressing cloth is connected to the iron and the pressing cloth can be moistened continuously and automatically.

In another embodiment, the iron has an attachment whereby the pressing cloth can be moistened by manually operated means. The iron can be moved freely to and fro relative to the cloth. This greatly economizes labor, and produces superior and more uniform work.

The pressing iron I may be of any conventional type. It is provided with a handle H, which is connected to the body of the iron by means of screws 19.

One of these screws 19 also serves to connect a plate I to the body of the iron. Said plate I is shaped to conform to the shape of the adjacent part of the body of the iron. Said plate I has integral arms 3, and said arms 3 have integral upstanding bearings 4. As shown in Fig. 5, the magazine roll 9 has a screw 11 which is removably fixed to one end face of said magazine roll. The shank of said screw 11 passes loosely through an opening in one of the bearings 4, so that the roll 9 can turn freely, in unison with bearing screw 11, relative to said bearing 4. As shown in Fig. 4 and Fig. 5, the roll 9 is hollow and a shank 9a is mounted in any suitable manner to the end wall 9b of the roll 9. The roll 9 can turn freely on shank 9a. A torsion spring 10 has one end thereof connected to the slotted end of the shank 9a which is shown at the left-hand side of Fig. 5. A cap 9c fits over the open end of the roll 9. Said cap may be resilient and it has a tight fit on roll 9, so that roll 9 and cap 9c turn in unison. A web 9d is fixed to the end wall of the cap 9c, and webs 9e are fixed to the web 9d.

Referring to Fig. 5, the right-hand end of the torsion spring 10 is connected in any suitable manner to the members 9e. The shank 9a is provided with a reduced end portion 9a, which extends through the central opening in the web 9d and the aligned opening in the end wall of the cap 9c. The extension 9a is integral with an end member 8, which is of rectangular cross-section.

Referring to Fig. 1, the bearing member 4 which is shown in said figure, is provided with a recess into which one-half of the member 8 fits. A holding member 5 is pivoted at 6 to said bearing member 4, and said member 5 is provided with a hook end 7, which can fit frictionally over an extension 7a of said member 4. Therefore, when the member 5 is in the op-

erative position shown in Fig. 1, it locks the shank **9a** against turning. The roller **9b** can turn freely on shank **9a**, in unison with cap **9c**, thus winding up the torsion spring **10**, since the end **10a** of said torsion spring is fixed to the member **9a**, and the other end of said torsion spring **10** turns in unison with cap **9c**.

The pressing cloth **12** is connected to the periphery of the magazine roll **9**, by a series of staples **18**, or in any other suitable manner, as clearly shown in Fig. 6.

The cloth is wound in the usual spiral form upon the magazine roll **9**.

In order to utilize the pressing cloth, a sufficient portion thereof is unwound from the roll **9**, so as to provide a pressing portion **12a** which is located underneath the pressing face of the iron. The free end of said pressing portion **12a** extends sufficiently beyond the rear edge of the iron, so that the iron can be moved longitudinally in its full pressing stroke, without losing contact with said pressing portion **12a**. In the embodiment shown in Figs. 1-7, the pressing cloth contacts with a sponge or other absorbent member **S**. Part of said sponge is located in a container **13** and part of said sponge projects out of said container. The sponge is kept suitably moistened. The cloth passes between a pair of guide rolls **14** and **15** which are turnably mounted in the arms **3**.

When the cloth is pulled to the operative position as shown in Fig. 1, the torsion of the spring **10** tends to turn the roll **9** so as to wind up the cloth thereon. Hence, when the iron does not press against the pressing cloth, said pressing cloth may be wound up on the magazine roll (if desired) until the stops **19**, which are removably connected to the cloth, abut the undersides of rolls **14** and **15**. This can be modified as desired.

For example, when the spring **10** is under no torsion, a sufficient length of the cloth can extend below the rolls **14** and **15**, and said free portion of the cloth may be of sufficient length to extend underneath the entire pressing surface, or any part of said pressing surface. The spring **10** may be under torsion when the stops **19** abut rolls **14** and **15**. The spring **10** may be under zero torsion when the free end of the pressing cloth extends any desired distance behind the rear edge of the iron. However, I prefer to have the spring **10** under torsion at all times, so that when the iron is raised from the work, the cloth is wound upon roll **9** until stops **19** abut guide rolls **14** and **15**.

Referring to Fig. 1, when the iron is moved to the left of the position shown therein, the pressure of the iron keeps the pressing portion **12a** stationary upon the cloth, and the movement of the iron to the left of the position shown in Fig. 1, merely unwinds more of the cloth from the magazine roll. When the iron is moved to the right of the position shown in Fig. 1, the roll **9** is turned so as to wind up some of the cloth. Hence, as the iron is moved longitudinally over the work, the cloth is always held taut above the front end of the iron, in the preferred embodiment. The operator can hold down the free end of the cloth at a suitable distance from the rear end of the iron, as the iron is moved to and fro. Likewise, the coefficient of friction between the iron and the pressing cloth is less than the coefficient of friction between the pressing cloth and the work which is being ironed. This makes it possible to raise the iron during the pressing operation, without winding the pressing portion

of the cloth upon the roll **9**. The rear or free end of the cloth can be held down upon the pressing table by any suitable releasable means.

The cloth is therefore rubbed back and forth along the sponge **S**. In any event, the cloth is sufficiently absorbent and it can conduct moisture sufficiently, so that the moisture will travel from the sponge **S**, to keep the pressing portion **12a** suitably moist.

Likewise, the iron can be raised at any time so as to allow roll **9** to wind up the cloth until stops **19** abut rolls **14** and **15**. By pulling the cloth **12** outwardly, the pressing portion **12a** is rubbed along the wet sponge **S**, in order to moisten the pressing portion thoroughly.

The embodiment shown in Fig. 8 is the same as the preceding embodiment, save that in Fig. 8 the vessel **13** contains water **W**. An atomizer consisting of the usual bulb **B**, and the tubes **16** and **17**, is provided. By operating the elastic bulb **B**, so as to force air through tube **16**, water is sprayed through the tube **17** upon the adjacent part of the pressing cloth.

The width of the pressing cloth exceeds the width of the pressing face of the iron, as shown in Fig. 2.

Any iron can have the improvements applied thereto as an attachment, including the well-known irons in which the pressing face is perforated, and in which water or steam is passed through the perforations, continuously or intermittently. Said water or steam would be absorbed by the pressing cloth. Said cloth can be moistened in any manner, as by sponging it directly, and I do not wish to be limited to the use of a moistening attachment on the iron.

The magazine roll and spring represent one of numerous types of devices which can be used to move the cloth automatically relative to the iron, so as to maintain the pressing portion of the cloth in taut condition. Other means for maintaining the pressing portion of the cloth in taut condition may be substituted, and I do not wish to be limited to the use of a magazine roll or spring.

I have shown preferred embodiments of my invention, but numerous changes and omissions could be made without departing from its spirit.

I claim:

1. In combination with a pressing iron, a magazine roll connected to said pressing iron, a pressing cloth connected to said magazine roll, said magazine roll being turnable relative to the iron so that the pressing cloth can be wound around said magazine roll or unwound therefrom, guide means also connected to said pressing iron and adapted to guide the movement of said pressing cloth when it is wound upon the roll or unwound from the roll, said magazine roll having a spring connected thereto and adapted to turn said magazine roll so as to wind up the pressing cloth thereon, said pressing cloth having stop means adapted to abut said guide means and to prevent the winding of the cloth upon the magazine roll beyond a predetermined point.

2. In combination, a pressing iron and a pressing cloth connected to said pressing iron, said pressing cloth having wholly separated ends, one end of said pressing cloth being attached to the iron, the other end thereof being free, said iron being movable longitudinally relative to said pressing cloth, said pressing cloth being of sufficient length to extend under the working face of said pressing iron, all the parts of said iron being located above its working face.

3. In combination, a pressing iron, a turnable roll mounted on said pressing iron and movable in unison with said pressing iron, a pressing cloth having separated ends, only one of the ends of said pressing cloth being connected to said roll, said roll being turnable and having means to wind up the pressing cloth thereon, means secured to said iron for moistening said pressing cloth, said pressing iron being movable longitudinally relative to said pressing cloth, said pressing cloth being of sufficient length to extend under the working face of said pressing iron, all the parts of said iron being located above its working face.

4. In combination, a pressing iron and a pressing cloth connected to said pressing iron, said pressing cloth having wholly separated ends, one end of said pressing cloth being attached to the iron, the other end thereof being free, said iron being movable longitudinally relative to said pressing cloth, said pressing cloth being

of sufficient length to extend under the working face of said pressing iron, said iron having spring means adapted to take up the slack in the cloth as the iron moves longitudinally with respect to said cloth, all the parts of said iron 5 being located above its working face.

5. In combination with a pressing iron, a magazine roll connected to said pressing iron above a working face of said iron, a pressing cloth connected to said magazine roll above said working face, said iron having spring means operative to turn said roll and to wind up the pressing cloth thereon, said pressing cloth being of sufficient length to extend under the working face of said iron. 10

6. The combination as claimed in claim 1 including means secured to said iron for moistening the pressing cloth.

MAX M. NEWMAN. 20
